UNITED STATES PATENT OFFICE.

WILLIAM SPARKS, OF JACKSON, MICHIGAN, ASSIGNOR TO THE SPARKS-WITHINGTON COMPANY, A CORPORATION OF OHIO.

ELECTRIC PUSH-BUTTON.

1,239,054.

Specification of Letters Patent. Patented Sept. 4, 1917.

Application filed April 25, 1913. Serial No. 763,538.

To all whom it may concern:

Be it known that I, WILLIAM SPARKS, of Jackson, in the county of Jackson, in the State of Michigan, have invented new and 5 useful Improvements in Electric Push-Buttons, of which the following, taken in connection with the accompanying drawings, is a full, clear, and exact description.

This invention relates to certain improvements in electric circuit closers commonly known as push buttons as applied more particularly to electrically operated horns and other apparatus of automobiles, aeroplanes, motor boats and similar vehicles where it 15 is customary to wear gloves or equivalent hand-protecting sheaths.

The operating member of an ordinary push button of this character is comparatively small in surface area and is movable 20 in a correspondingly small aperture or socket in a relatively larger case so that it must be operated in a direct line axially in order to close the circuit.

Under these conditions it is practically 25 impossible or at least inconvenient to operate the button without removing the glove or mitten from the hand and the main object of my present invention is to provide a push button which may be operated by the 30 gloved hand or by the foot of the driver through pressure upon any portion of the surface of the cap or button.

Another object is to make the case including the cap serve as a dust and weatherproof 35 housing for the electrical contacts and other interior parts without adding materially to the size or cost of manufacture of the device.

A further object is to utilize the retracting spring for the cap as a part of the circuit connections between the contacts.

Other objects and uses relating to specific parts of my invention will be brought out in the following description.

In the drawings Figure 1 is a perspective 45 view of the detached circuit closer or push button.

Fig. 2 is a diametrical section through the same device taken on line 2—2, Fig. 1.

Fig. 3 is a sectional plan of the case sections, showing the insulating base and contact ring thereon.

Fig. 4 is a plan partly in section of the detached insulating base and the retracting spring leading to one of the binding posts.

Fig. 5 is an inverted plan of the detached 55 cap.

This push button or circuit closer comprises a tubular case —1— having one end closed by a suitable base plate —2— for receiving and supporting an insulating base 60 —3— and its opposite end closed by a cap —4— telescoping externally therewith and adapted to tilt in any direction relatively to its axis.

A contact ring or annulus —5— is secured 65 by suitable fastening means as a screw —6— to the inner or upper face of the insulating base —3— and is provided with a central opening of sufficient size to receive a coil spring —7— without contacting therewith, 70 one end of the coil spring being seated in a socket —8— in the insulating base —2—.

An insulating bushing —9— is secured in a central socket —10— in the inner face of the cap —4— and is adapted to support a 75 concavo-convex contact member —11— which is secured to the post by suitable fastening means as a screw —12— with its concave side facing the contact member —5—.

The upper or inner end of the coil spring —7— bears against and is electrically connected to the contact member —11— and serves to normally separate the contacts one from the other and also to return the cap 85 —4— to its normal position.

The intermediate portion of the case —1— is compressed inwardly to form an annular shoulder —13— against which the inner face of the insulating base —3— is 90 normally seated and is held in this position by the base plate —2— which is secured to radially projecting flanges —14— on the base of the case —1— by suitable fastening means, as screws —15—.

The case —1— and also the insulating base —3— are cylindrical, the outer end of the case being provided with an out-turned flange —16— co-operating with a similar in-turned flange —17— on the cap —4— to 100 limit the outward movement of said cap and to normally hold it substantially parallel with the base plate —2— or in a plane at right angles to the axis of the case, sufficient clearance being left between the inner edges 105 of the flanges —17— and periphery of the case to allow the cap to be tilted or moved axially toward the base plate for closing the

contacts against the action of the retracting spring —7—.

This retracting spring forms a part of the circuit connections between the contacts and for this purpose one end of the spring is extended laterally into a radial aperture —18— in the insulating base —3— as shown in Fig. 2 and is engaged by a binding post —19— which is screwed into said insulating base or insulated from the contact member —5—.

The screw —6— also forms a binding post and to these binding posts are attached the circuit wires —a— which are brought out through an aperture —b— in the periphery of the case and connected in any suitable manner to a source of electric energy and to a horn or other device which may be desired to operate.

20 The contact member —11— is insulated from the cap by the bushing —9— which together with the base —3— may be made of fiber or other suitable insulating material, said contact member —11— being circular in plan and of greater radius than that of the opening in the ring —5— but of less radius than the outer diameter of said ring, the ring being of sufficient width to assure contact with the rim or edge of the plate —11— when the cap is tilted or moved from its normal position toward the base plate.

It will be observed that the contacts are coaxial and normally spaced a slight distance apart just sufficient to maintain a normally open circuit while the cap —4— is of considerably greater diameter than either of the contacts, thus permitting it to be depressed or tilted by contact with the finger, the entire hand or any portion of the knee or foot to engage the rim of the contact member —11— with the adjacent surface of the contact member —5— for closing the circuit and thereby operating the horn or other translating device which may be connected in the circuit, said cap —4— and contact —11— being turned to their normal positions to open the circuit as soon as the pressure on the cap is relieved.

It will be seen upon reference to Fig. 2 that the difference between the flange —17— and the top of the cap —4— is considerably greater than the flange —16— on the case —1—, such distance being greater than the normal distance of separation between the contacts so as to allow sufficient movement of the cap either by tilting or direct inward

pressure to close said contacts one upon the other, the spring —7— and limiting stops —16— and —17— serving to hold the cap and contact member —11— normally to the axis of the contact ring —5— and case —1—.

By closing the opposite ends of the tubular case —1— through the medium of the base plate —2— and cap —4—, the interior parts, such as the contacts, binding posts and insulators, are protected against dust and moisture, thereby assuring greater efficiency and durability of the device and, at the same time, permitting the interior parts to be readily inspected or removed at any time by simply loosening the screws —15— and withdrawing the base plate —2—, whereupon the insulating base —3— and other interior parts may be readily withdrawn for inspection and repairs when necessary, the bushing —9— being preferably screwed into the socket —10— to hold it in place.

The operation of my invention will now be readily understood upon reference to the foregoing description and the accompanying drawings and, while I have shown the retracting spring —7— as forming a part of the circuit connections between the contacts, it is evident that these connections may be otherwise made without departing from the spirit of my invention and, therefore, I do not limit myself to the process of construction and arrangement shown and described.

What I claim is:

A circuit controller comprising a tubular casing having substantially cylindrical portions of different diameters, the portion of lesser diameter formed with its free edge with an outwardly extending flange, a block of insulating material mounted within the portion of larger diameter, a cap telescoping externally with the case and tilttable and rectilinearly movable relatively thereto and having a laterally and inwardly extending flange engaged with the flange upon the case to prevent separation of the case and cap, and normally spaced contacts within the case brought together by relative movement of the cap from its normal position on the case.

In witness whereof I have hereunto set my hand this 23rd day of April, 1913.

WILLIAM SPARKS.
